IRONING BOARD STAND ATTACHMENT

Selig A. Schlags, Brooklyn, N. Y.

Application November 27, 1948, Serial No. 62,359

4 Claims. (Cl. 38—125)

1

The subject of the present invention is a novel and valuable device for preventing soiling the end of the ironing board cover, by permanent attachment of the device to an ironing board so as to be swingably mounted on the underside of the latter, whereby said device may at will be readily arranged in any one of a plurality of different dispositions relative to the board. In one of such dispositions of the new device, it provides at one end of the board, as at the butt end thereof, a footing means projected beyond that end of the board, so that said means will rest on the floor and thus protectively elevate the entirety of the board as well as all of its folding understructure if the ironing board be one of the almost universally now preferred collapsible type. In another of said dispositions of the new device, it may depend vertically below the end of the board at which it is carried, for then serving as a conveniently placed hanger for a cloth to be dampened for use in the ironing work; and, moreover, with the very important aim achieved that no part of said footing means may be protruded in such manner that accidental injurious contact therewith by a part of the person of the ironer is not possible.

A feature of the invention is that the new device may be embodied in a variety of practical forms thereof; with each, however, of exceedingly simple and inexpensive yet rugged construction, and with each, nevertheless, capable of being easily and quickly properly attached to an ironing board of any kind and then for always reliably functioning exactly for the purpose at any time desired.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view showing the underside of an ironing board of the kind having a folding understructure, the latter being shown conventionally and in collapsed condition; and with the butt end of said board equipped with one now favored embodiment of the invention—the ironing board being here shown in upright position but now protectively elevated above a supporting floor by way of the footing means already mentioned.

Fig. 2 is an enlarged fragmentary perspective view, showing the parts seen near the bottom of Fig. 1 and as there arranged.

2

Fig. 3 is a view like Fig. 2, but showing one possible modification.

Fig. 4 is also a view like Fig. 2, but showing another modification.

Fig. 5 is a bottom perspective view, showing the application of the device.

Fig. 6 is an enlarged vertical sectional view taken on the line 6—6 of Fig. 5.

Fig. 7 is an enlarged fragmentary elevational view, looking at the underside of an upright ironing board as in Fig. 1, but showing still another of the many possible forms which an embodiment of the invention may assume.

Referring to the drawing more in detail, and first to Figs. 1 and 2, 10 designates an ironing board and 11 a conventional folding understructure.

The new attachment as here shown, and as a whole marked 12, comprises an attachment plate 13, on which is swingably mounted an elongated member 14 of U-shaped configuration shown as made of a single length of a suitable material, as round rod metal stock, and formed into the shape illustrated, thereby to include a pair of legs for constituting at their free ends the footing means aforesaid. Said member 14 has a straight pintle-like central portion joining the root ends of said legs, and at said pintle portion the member 14 is swingably mounted on the plate 13 at a strap or loop portion 15 of the latter struck out integrally therefrom. The free extremities of the member 14 are provided with rubber caps 12a to prevent the ironing board from slipping on the floor and from scratching the floor covering, rug 35 or the floor.

The plate 13 is so placed at the underside of the board 10 that when the parts are arranged as shown in Figs. 1 and 2, the end portions of the legs of the member 14 suitably project beyond an end of the board, as beyond the butt end 16 thereof. For holding the member 14 in this disposition, a swing latch lever 17 is suitably pivotally mounted on the plate 13, as by way of the single rivet indicated at 18. Suitably secured across the member 14 and to the two legs thereof intermediate the ends of the latter, is a bar 19 desirably of standard strip metal stock as indicated. This bar acts as a friction affording keeper for the swing latch 17 when swung to the position shown; said swing latch being desirably twice laterally bent as illustrated. An ironing board is ordinarily if not always of wood; and for securely permanently attaching the device thereto, the plate 13 may be apertured for being secured in place by a suitable plurality of screws, as indicated at 20.

When the folding understructure is to be expanded and the board is arranged for ironing atop the erected understructure, the swing latch 17 is released, so that following such erection the member 14 will depend vertically from its point of pivotal support. Then the legs of said member will be safely out of the way, while the bar 19 will present a convenient hanger for a damp cloth to be used in the ironing work.

Referring to Fig. 3, wherein, in connection with the modification here illustrated, the parts to which are applied reference numerals with primes added correspond, respectively, to the parts to which in Figs. 1 and 2 are applied reference numerals without primes, it will be noted that the structure proposed is very much like that of Figs. 1 and 2; with the exception that the pivotal mounting 15' for the member 14' is made as a piece separate from the plate 13', such piece being a short length of standard strip metal stock transversely bent to provide a central portion C-shaped in cross-section and also to provide terminal portions in the shape of parallelly extended end flanges. By way of said flanges the piece 15' may be suitably attached to the plate 13', as by spot or shot welding at such locations as indicated by the several small x's shown.

Referring to Figs. 4-6, wherein, in connection with the modification there illustrated, the parts to which are applied reference numerals with double primes added correspond, respectively, to the parts to which in Figs. 1 and 2 are applied reference numerals without primes, it will be noted that the structure here proposed in one respect resembles the structure of Fig. 3 in that the pivotal mounting 15'' for the member 14'' is a separate piece. However, said piece 15'' is shown as secured at its end flanges to the plate 13'' by riveting. The member 14'' is in this case shaped differently from the members 14 and 14'. Said member 14'', which may be bent from a standard round rod metal stock, is illustrated as being in the shape of almost a closed O, but an O fairly widely straight and horizontal along its bottom and with upwardly converged sides, and with the tops of these sides prolonged by inwardly mutually facing parallelly offset terminal portions of the length of round rod stock employed. Said terminal portions combine to constitute the pintle-like component of the member 13'', while the outer wide end of the latter constitutes the footing means aforesaid. Said wide end of the member 13'', when the ironing board is erected and said member depends vertically, may be used as the hanger for a damp cloth or the like in lieu of employing for such use the bar 19''. The swing latch 17'' is shown to be secured to the plate 13'' by a flat head rivet which is swivelly arranged between the counter-sunk or dimpled portion of the plate 13'' and the bottom of the ironing board 10'' so that the rivet 18'' may be inserted in position through the back of the plate 13'' and permit free rotation of the swing latch 17''.

Referring to the embodiment shown in Fig. 7, the parts here marked 10^a, 11^a, 14^a and 16^a correspond, respectively, to the parts of Figs. 1 and 2 marked 10, 11, 14 and 16. Here the member 14^a, which, also, may be bent from a standard round rod metal stock, is shaped as illustrated to include a central straight portion 21, a pair of adjoining leg portions 22 extended divergently from said straight portion, and fairly short terminal portions 23 parallelly outwardly offset

from the ends of the legs remote from said central straight portion 21. Said round rod metal stock may be of some resiliency, and then the member 14^a may be shaped to bias its leg portions toward a spread greater than that illustrated in the drawing, whereby, at apertured fitments 24 suitably carried by the board, said terminal portions 23 of the member 14^a may be snapped into swingable attachment to the underside of the board. Said fitments 24 may be specially supplied ones, or may be constituted by the familiar blocks or the like attached to the board for facilitating pivotal attachment thereto of elements of the folding understructure 11^a. In the latter case, an ordinary hand drill could be used at said fitments, to provide the apertures therein for the terminal portions 23 of the member 14^a.

A latch means is not shown in connection with the modification now being described, but, as will be understood, such a latch means may be added. However, the pivotal connections between the terminal portions 23 of the member 14^a and the fitments 24 could include apertures in the latter of such cross-section that said member 14^a would dependably remain in its position indicated in dot and dash lines at 14^b after being thus disposed and while acting to present the protective footing means of the invention. The member 14^a as shown in full lines, is in a disposition substantially 180° removed from its said position 14^b. The position to which the member 14^a could be swung, so as to depend vertically from the underside of the ironing board while in use, is indicated in dot and dash lines at 14^c.

It is to be understood that without this ironing board attachment, the user must stand the ironing board on the floor to open or close, and in so doing, the end of the ironing cover gets soiled. When a person places wearing apparel around the soiled cover, the apparel picks up any particles of dirt around it. Also, when ironing has been completed and the ironing board is to be stored away for future use, the ironing board does not have to stand on the floor, but instead rests on the attachment and in this way tends to keep the end of the cover clean.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A device of the class described, comprising a plate for attachment to the underside of an ironing board slightly inward of the butt end thereof, an elongated member pivotally attached at one end to said plate, said elongated member being of a length greater than the distance between the point of pivotal attachment of the said one end of said elongated member and the butt end of the ironing board so that the free end of said member will project beyond the butt end of the ironing board with said elongated member pivoted to a position extended parallel to the length of said board, and means on said plate and engaging said elongated member for retaining said elongated member in a position with its length extended parallel to the ironing board, said elongated member being of U-shape, and a strap struck from said plate forming a passage-

way through which the intermediate arm of said U-shaped elongated member passes forming the pivotal attachment of said member on said plate.

2. A device of the class described, comprising a plate for attachment to the underside of an ironing board slightly inward of the butt end thereof, an elongated member pivotally attached at one end to said plate, said elongated member being of a length greater than the distance between the point of pivotal attachment of the said one end of said elongated member and the butt end of the ironing board so that the free end of said member will project beyond the butt end of the ironing board with said elongated member pivoted to a position extended parallel to the length of said board, and means on said plate and engaging said elongated member for retaining said elongated member in a position with its length extended parallel to the ironing board, said elongated member being of U-shape, and a strap struck from said plate forming a passageway through which the intermediate arm of said U-shaped elongated member passes forming the pivotal attachment of said member on said plate, and protective caps engaged over the free ends of the side arms of said U-shaped elongated member.

3. A device of the class described, comprising a plate for attachment to the underside of an ironing board slightly inward of the butt end thereof, an elongated member pivotally attached at one end to said plate, said elongated member being of a length greater than the distance between the point of pivotal attachment of the said one end of said elongated member and the butt end of the ironing board so that the free end of said member will project beyond the butt end of the ironing board with said elongated member pivoted to a position extended parallel to the length of said board, and means on said plate and engaging said elongated member for retaining said elongated member in a position with its length extended parallel to the ironing board, said elongated member being of U-shape, and a strap struck from said plate forming a passageway through which the intermediate arm of said U-shaped elongated member passes forming the pivotal attachment of said member on said plate, and a bar mounted across the side arms of said U-shaped elongated member intermediate of

their ends, so constructed and arranged that with the ironing board in use in a horizontal position said elongated member will be depended therefrom so that said bar can be used as a hanger for a pressing cloth.

5 4. A device of the class described, comprising a plate for attachment to the underside of an ironing board slightly inward of the butt end thereof, an elongated member pivotally attached at one end to said plate, said elongated member being of a length greater than the distance between the point of pivotal attachment of the said one end of said elongated member and the butt end of the ironing board so that the free end of said member will project beyond the butt end of the ironing board with said elongated member pivoted to a position extended parallel to the length of said board, and means on said plate and engaging said elongated member for retaining said elongated member in a position with its length extended parallel to the ironing board, said elongated member being of U-shape, and a strap struck from said plate forming a passageway through which the intermediate arm of said U-shaped elongated member passes forming the pivotal attachment of said member on said plate, and a bar mounted across the side arms of said U-shaped elongated member intermediate of their ends, so constructed and arranged that with the ironing board in use in a horizontal position said elongated member will be depended therefrom so that said bar can be used as a hanger for a pressing cloth, said retaining means comprising a latch lever pivotally attached at one end to said plate and being of a length to have its other end overlie said bar when said elongated member is extended parallel to the length of the ironing board.
